UNITED STATES PATENT OFFICE.

CHARLES F. MOORE AND CHARLES H. STUBBS, OF BOSTON, MASSACHUSETTS, AS
SIGNORS TO THE DAMPNEY COMPANY OF AMERICA, OF BOSTON, MASSACHUSETTS,
A CORPORATION OF MASSACHUSETTS.

TUBE-COATING APPARATUS.

Application filed July 16, 1925. Serial No. 43,962.

This invention in general relates to apparatus for applying a protective coating to the inside of boiler tubes and the like, and its object is to provide an apparatus where-
5 by the interior of the tubes may be coated, in the nature of a painting operation, uniformly, efficiently, quickly and conveniently, and with a minimum amount of labor.

To these ends we provide a rotary brush
10 and an air turbine adapted to enter the tube, and a source of compressed air and a moisture remover, conveniently located, connected with the air turbine by means of a comparatively stout, flexible, air conduit.

15 In the accompanying drawings,

Figure 1 is a general view of the apparatus, showing the brush and air turbine inserted in a tube and the moisture remover in section;

20 Fig. 2 is a view illustrating the air turbine in section and the rotary brush, in elevation, inserted in a tube;

Fig. 3 is an end view of the rotary brush in closed position;

25 Fig. 4 is an end view of the rotary brush in fully expanded position;

Fig. 5 is a sectional view of the air turbine taken on the line 5—5 of Fig. 2, looking in the direction indicated by the arrows;

30 Fig. 6 is a sectional view of the air turbine taken on the line 6—6 of Fig. 2, looking in the direction indicated by the arrows;

Fig. 7 is a partial sectional view of the air turbine taken on the line 7—7 of Fig. 2,
35 looking downwardly; and

Fig. 8 is a sectional view taken on the line 8—8 of Fig. 2, looking in the direction indicated by the arrows.

Referring now to the drawings in detail,
40 in which like reference numerals designate similar parts throughout the several views, 10 denotes a boiler tube expanded at one end into the end plate 11. The tube is prepared for the coating operation by being thor-
45oughly cleaned of foreign matter and in-
crustations on the inner periphery of the tube. Then the coating, in liquid form, in proper amount taking into consideration the length and diameter of the tube, is poured or squirted into the tube, conveniently by means of a device in the nature of a grease gun, and it then becomes the function of

the apparatus of this invention to spread the coating uniformly over the entire inside surface of the tube.

55 The brush, indicated generally by the reference numeral 13, is driven by a conventional air turbine 14 which is connected at its intake side with the flexible conduit 15 leading from the moisture separator 16
60 which, in turn, is connected with a supply of compressed air.

In Figure 1 we have illustrated a compressor 17 having an air inlet 18 and a discharge pipe 19 leading to a reservoir or
65 storage tank 20 having a blow off valve 20^a to maintain a supply of compressed air at a predetermined pressure. The reservoir 20 communicates with the intake of the moisture separator 16 through a pipe line 21 in
70 which a control valve 21^a is provided. The compressor 17 may be operated in any conventional manner as, for example, by a motor 22.

75 Since the air turbine, when in use, is inside the tube, it follows that the exhaust therefrom is discharged into the tube. The compressed air in the reservoir or storage tank 20 will carry more or less moisture, and perhaps oil, and, if the exhaust from the
80 air turbine were to carry such moisture, deposit thereof on the inner surface of the tube would preclude the proper coating thereof since it is necessary that the coating be applied directly to the clean, dry
85 and bare metal of the tube. The present apparatus avoids the difficulty and secures the

designed and a specially advantageous result. The compressed air in entering the moisture separator 16 follows the path indicated by the arrows therein. The operation
90 of the moisture separator per se is familiar to those skilled in the art. The current of entering air impinges upon the surface of the elbow 23 and causes a part of the water
95 in the air to accumulate on this surface. This water is drained from the surface through a pipe 24 and into the water space
25, from which the water may be removed whenever it is desired by a suitable pet cock 100

26. Associated with the water space 26 is a gauge 27 for indicating the water level therein. More of the water within the air is entrained by the cylindrical sieve 28 as the

air passes downwardly, and this water is also discharged in the water space 25. The air in passing around the lower edge of the cylinder 29 is subjected to a whip-snapping action which causes any moisture, that has not been previously entrained, to be thrown off into the perforated trough 30, which empties into the water space 25. The clean air then passes out of the discharge pipe 31 which is connected to one end of the flexible tube 15.

The clean air, after it leaves the moisture remover 16, is transmitted to the air turbine 14 by means of the flexible tube 15, which is comparatively stout so that it may serve as a handling means and the end of which is threaded into the head 38. This air turbine of generally cylindrical form and of such size that it may fit loosely within the tube, may be of any conventional design. The air makes its entry into the main housing 40 through the passage 35 and then passes through the two supply ports 36 and 37 (Figs. 2 and 5). Suitably journaled in the main housing, in bushings 57 and 58, is a rotatable shaft 41 to which is secured intermediate its ends a rotor 42. This rotor 42 is positioned inside of a shell 43 (Fig. 5) the bore of which is elliptical in shape. As shown in Fig. 5, the apertures 36 and 37 which constitute the supply ports of the turbine are so designed as to cause the rotor to revolve in the direction indicated by the arrows. High rotative speed is imparted to the shaft 41 by the action of the compressed air behind the paddles 45 carried in slots 46 in the rotor in the elliptical shell, and two of these paddles are always under pressure, the paddles always tending to move outwardly to follow the interior surface of the elliptical shell. Positioned intermediate one end of the rotor 42 and the housing 40 is a circular plate 50 (Fig. 2) equipped with ports 51 and 52 (Figs. 6 and 7), which communicate with the exhaust passages 53 and 54 in the housing 40. The air upon entering the supply ports 36 and 37, acts upon two of the paddles 45 causing the rotor 42 to revolve one-half a revolution. At the same time the other two paddles are brought into position to be acted upon, and so forth. The air, after having acted upon the paddles discharges through the ports 51 and 52 and the exhaust passages 53 and 54.

Referring now to the brush, pivotally secured to the free end of the shaft 41 are a pair of arms 71 and 72. The arm 71 has a pair of lateral ears 73 and 74 and the arm 72 has a pair of lateral ears 75 and 76 which fit over the end of the shaft, and a pivot bolt 78 passes through these ears and the end of the shaft as shown in Figure 8.

The arms 71 and 72 are drawn together at 80 (Fig. 2) and then extend parallel to each

other in an outward direction, where they are formed into channel portions 81 and 82, respectively. Mounted in each channel is a base 83 of a brush 84.

Extending from the end of the arm 71 is a lateral projection 90 having an opening 91 (Figs. 2, 3 and 4). Extending from the end of the arm 72 is a lateral projection 92 which passes through the opening 91 in the projection 90. The end of the projection 92, indicated by reference numeral 93 in Fig. 2, is bent into a hook to catch within the opening 91 and limit the distance which the arms may be separated. 70 75

The brush as a whole is of a size to fit 80
easily within the tube and the construction
and operation thereof is such that it will
accommodate itself to varying sizes of tubes
within reasonable limits. It is apparent that
when the shaft 41 revolves the arms 71 and 85
72 and the brushes carried thereby will
swing outwardly, due to centrifugal force,
against the inner wall or surface of the
tube 10.

After the coating, in liquid form, has been introduced into the tube as hereinbefore described, the brush is inserted in the end of the tube, using the conduit 15 as a handle. The valve 21^a is then opened to supply the compressed air and the brush revolves, the brush elements being pressed against the inner surface of the tube by centrifugal force. With the brush revolving, it is fed slowly up the length of the tube and back again, and experience has demonstrated that this is entirely sufficient for the uniform and complete coating of the entire inner surface of the tube. The exhaust from the air turbine, being dry, not only does not interfere with the proper spreading of the coating directly on the metal of the tube, but acts as an agent to dry the spread coating, thus materially assisting in even distribution and rapid finishing.

We claim;

1. In combination, a tube coating apparatus, a rotor driven by air, and a brush with radially extending bristles expansible by centrifugal force associated therewith and driven thereby for applying a coating to the inner periphery of the tube, both the brush and rotor being adapted to enter the tube, the air exhaust of the said rotor being adapted to discharge directly into the said tube to augment drying of the coating applied thereto by the said brush. 110 115 120

plied thereto by the said brush.

2. A tube coating apparatus comprising an air turbine adapted to enter a tube, and rotary brush elements hinged to and driven by said turbine to separate by centrifugal force. 125

3. A tube coating apparatus comprising an air turbine adapted to enter a tube and carried on the end of a flexible air conduit, and rotary brush elements hinged to and

driven by said turbine to separate by centrifugal force.

4. A tube coating apparatus comprising an air turbine of generally cylindrical form adapted to enter a tube and carried on the end of a flexible air conduit of lesser diameter than said turbine, and rotary brush elements hinged to and driven by said turbine to separate by centrifugal force.

10 5. A tube coating apparatus comprising an air turbine adapted to enter a tube, and a rotary brush hinged to and driven by said turbine and having brush elements automatically moving outwardly when rotated.

15 6. A tube coating apparatus comprising an air turbine of generally cylindrical form adapted to enter a tube and carried on the end of a flexible air conduit also adapted to enter the tube, said turbine discharging its

exhaust into the tube, and a rotary brush 20 hinged to the rotating element of said turbine and having brush elements automatically moving outwardly when rotated.

7. A tube coating apparatus comprising an air turbine adapted to enter a tube and 25 carried on the end of a flexible conduit adapted for connection to a source of compressed air, and a brush expandible by centrifugal force carried and driven by said turbine, the exhaust from said turbine being 30 restricted and discharging directly into the tube toward the wall thereof in proximity to said brush.

In witness whereof, we hereunto subscribe our names, this 9th day of July, 1925.

CHARLES F. MOORE.
CHARLES H. STUBBS.
